GAME TABLE

Joseph J. Sparacino, West Berlin, N.J.
(3001 Tennessee Ave., Fort Pierce, Fla. 33450)

Filed May 11, 1970, Ser. No. 22,931

Term of patent 14 years

Int. Cl. D21—01

U.S. Cl. D34—5

Fig. 2

Fig. 3

Fig. 4

Fig. 5

FIG. 1 is a perspective view of the game table looking from above and showing one end and one side thereof;

FIG. 2 is a side view of the table;

FIG. 3 is a fragmentary plan view of the table, showing the portion at right of FIG. 1;

FIG. 4 is an end view as seen from the right of FIG. 1; and

FIG. 5 is a bottom view of the table.

An essential feature of my design resides in the cylindrical projections, as shown, forming an integral part of the playing surface in combination with the particular game table.

I claim.

The ornamental design for a game table, as shown and described.
